CLAIM

The ornamental design for an under computer monitor power controlling base, as shown.

DESCRIPTION

FIG. 1 is a top, front, right side perspective view of an under computer monitor power controlling base showing our new design;

FIG. 2 is a top plan view thereof;

FIG. 3 is a front elevational view thereof;

FIG. 4 is a left side elevational view thereof;

FIG. 5 is a rear elevational view thereof; and,

FIG. 6 is a bottom plan view thereof.
